UNITED STATES PATENT OFFICE.

ALBERT OSVALD, OF LOS ANGELES, CALIFORNIA.

MOP WRINGER.

Application filed June 20, 1927. Serial No. 200,182.

This invention relates to a cloth wringing mechanism and has for an object to provide a simple, practicable and substantial unitary organization adapted to be solidly and permanently secured within and below the rim of a suitable bucket, it being understood that the wringer unit may be made in sizes adaptable to various sizes of buckets.

An object is to provide a wringer more especially designed for the wringing of mops and to provide a central arrangement of effective rollers in a bucket to avoid over-slopping of water from the mop being wrung.

A further purpose is to provide a wringer unit including frame parts attachable to the interior wall surface of a bucket and having pivoted thereon a bail operating a roller and serving as a handle for the bucket to eliminate mounting of one on the bucket itself.

An additional object is to provide a wringer of few differentiated parts so that the cost of manufacture can be kept low and to enable a low retail price.

Another object is to provide a wringer attachment which can be bodily installed either in course of bucket manufacture or to stocks of buckets in storage, warehouse or store supply by the mere drilling or punching of holes for bolts or rivets by which the assembled unit as a whole can be secured to the bucket.

Additional objects, features and advantages will be made manifest in the following specification of the herewith illustrated embodiment; it being understood that modifications, variations and adaptations may be resorted to within the scope, spirit and principle of the invention as it is more particularly claimed hereinafter.

Figure 1 is a perspective of the open wringer unit, ready for installation.

Figure 2 is a plan of a bucket showing the unit installed and in closed position.

The unit, as adapted for a given size bucket B, has a pair of side rails 2 and 3 of duplicate character except that their ends are oppositely inturned so as to lie against the interior surface of the bucket wall where they are secured just below the top edge as by bolts or rivets 4. The rails are slotted, at 5, longitudinally to receive a floating shaft 6 carrying a compressing roller 7.

The ends of the shaft 6 project through the rails to connect with the lower ends of links 8 lying outside of the rails and extending up and connecting at pivots 9 to the

near shanks of a bail 10 whose lower ends are pivoted at 11 to rails 2-3 about midway their length so that when the unit is attached to a bucket B the bail not only serves to shift the roller 7 sidewise but will also function as a handle for the bucket.

The roller 7 is movable over toward a butress roller 13 having a shaft 14 hung in the rails 2-3.

The bail 10 is shown as pivoted on the rails substantially along a diameter of the bucket so that this will balance when lifted by the handle.

Preferably, though optionally, a means is provided to automatically bring the bail to an upright position and is here shown as including a bell-crank spring having a coil 15 with an arm 16 hooking back of the bail and an arm 17 hooking under the near rail 2; the arm 16 being tensioned to draw the bail up.

The rollers are so relatively disposed in the bucket that when the bail 10 is pressed down, as in Fig. 2, they come together about 30 medially of the bucket. This is to keep the water wrung from the interposed cloth from over-slopping; the rollers terminating well within the bucket at their ends.

What is claimed is:

1. A mop-wringing bucket attachment including a pair of side rails having longitudinal slots, a pair of parallel compressing rollers one of which is slidably mounted in the slots of the rails, a bail pivoted on the rails medially between their ends to form a handle for the bucket and having links connected to the sliding roller whereby it can be bodily shifted to and fro; said rails being fittable as a unit inside the wall of the bucket with the bail on a diameter of the bucket.

2. A mop-wringing bucket attachment including a pair of side rails having longitudinal slots, a pair of parallel compressing rollers one of which is slidable in the rail slots, a bail pivoted on the rails on a line below the plane of movement of the sliding roller and having links outside of said rails and connected to the sliding roller, said rails having ends to rest against the bucket wall, and means passing through said ends to secure the attachment in place in the bucket.

3. A wringer device attachable as a unit inside of a bucket and having a pair of slotted side rails having ends to fit the bucket wall, a bail pivoted medially of the length of the rails to form a diametrical handle for

the bucket, a buttress roller mounted in and between the rails and to one side of the bail axis, a roller slidably mounted in the rails and at the opposite side of the axis of the bail, and links connecting the bail to the latter roller to move it toward and from the buttress roller to compress an object thereagainst, said rollers, when closed, being substantially diametrical to the bucket to avoid 10 over-slopping from wringing actions.

4. In a mop wringer, side rails attachable to the inside of a bucket wall, rotatable buttress roller hung therebetween and a compression roller laterally shiftable therein, a 15 bail pivoted on and medially between the ends of the rails and operatively connected to the shiftable roller with the bail on the diameter of the bucket, and means for automatically bringing the bail upright and 20 opening the slide roller, and including a

spring coil on the pivot of the bail and having radial arms, one engaging the bail and the other a near rail.

5. In a mop wringing attachment for a bucket, a pair of parallel rails, means to secure the ends of each rail to the inner face of a bucket wall, a bail pivoted on and medially of the length of the rails so as to form the bucket handle when the rails are secured to the bucket wall, a buttress roller 25 journaled in said rails in a fixed position to one side of the bail axis, said rails having slots extending from the bail anchorage toward the opposite ends from the buttress roller, a compression roller having a shaft 30 sliding in the slots and extending therethrough, and links connected to the said shaft outside of the rails and to and inside of the bail arms.

ALBERT OSVALD.
